INVENTOR
FREEMAN H. OWENS.

BY *Philip S. Hopkins*
ATTORNEY

UNITED STATES PATENT OFFICE

FREEMAN H. OWENS, OF NEW YORK, N. Y., ASSIGNOR TO OWENS DEVELOPMENT CORPORATION, OF NEW YORK, N. Y., A CORPORATION OF NEW YORK

SPRING

Application filed November 12, 1926. Serial No. 147,982.

My invention refers generally to springs, and particularly to that type of spring suitable as a motor or source of power which, when put under compression or wound up, 5 expends its energy to drive or rotate a shaft, gearing, pulleys or other devices.

Coil springs of various types have been heretofore used as motors and a problem in such use has always been in the provision 10 of a spring of sufficient length and stiffness or strength to accomplish the purpose desired and provide the required power for the necessary period of time, and at the same time to accommodate such a spring within the space 15 provided, usually very small.

The primary object of my invention is to provide a spring motor which overcomes all of the problems above mentioned, and which is simple and inexpensive to manufacture.

Another object is to provide a spring in 20 which the coils or convolutions of the wire lie adjacent or along side one another and so formed that upon winding or unwinding, it is impossible for the adjacent coils or convolutions to ride upon or over each other.

A more specific object is to provide a spring of the lateral coil type in which the coils thereof are formed at given points about their circumference with depressions 30 or indentations whereby the length of wire in a spring of a given length may be considerably greater than that of the ordinary circular coils forming a spring of this type.

A still further object is the provision of a 35 novel method of forming such a spring.

Other objects and advantages in details of construction and operation will be apparent as the description proceeds, reference now being had to the accompanying drawings 40 wherein like reference numerals indicate like parts.

In the drawing:—

Figure 1 is a detail sectional view illustrating one embodiment of my invention.

Figure 2 is a similar view illustrating another embodiment thereof.

Figures 3 and 4 are similar views illustrating still further modifications of my improved spring.

Figure 5 is a detail side view of a spring made in accordance with my invention.

Figure 6 is a detail end view partly in section illustrating clearly the preferred method of forming my improved spring.

Figure 7 is a detail end view illustrating a modified method of forming the spring.

In Fig. 1, the reference numeral 1 refers to the spring wire, one end 2 of which is shown secured to a shaft 3 adapted to be rotated by the spring 1 when the same is wound and its tension released. Any suitable winding mechanism may of course be provided for tensioning the spring and it will be understood, of course, that the motion imparted to the shaft by the spring may be utilized in the driving of gears, pulleys, or any desired apparatus.

The spring 1 is in this modification provided with three depressions or indentations 4 70 which obviously permit a greater length of wire to be wound into a given length of spring. This, of course, tends to lengthen the period of power or exertion of the spring in a single winding and permit the use of 75 such spring in a space no larger than is required for the conventional circular spring of the same length.

Obviously too, due to the indentations 4, 80 such a spring eliminates the climbing or riding of the adjacent convolutions of the wire up over each other during the winding or unwinding action. The winding common to ordinary circular springs of this type is therefore eliminated.

In Fig. 1 but 3 indentations 4 are provided. It will be clear, of course, that more than 3 85 may be provided, if desired, instances of 6 and 8 indentations being illustrated in Figs. 2 and 3 respectively, the reference characters 4a and 4b designating such indentations.

Obviously, the greater the number of indentations, the greater the length of wire in a given length of spring.

In Fig. 4, the indentations 5 are shown to be a great deal deeper than those in the preceding figures. This is sometimes advisable particularly in the case where the shaft 6 is very small and there is ample room for a 100

spring of a larger outside diameter than the shaft.

Figure 5 illustrating a side view of the spring shown in Fig. 3 wherein the shaft 3 has secured thereto one end 2 of the spring material 1, provided with the indentations 4b. The opposite end 7 of the spring is shown secured to a sleeve 8 rotatable upon the shaft 3 whereby the spring may be wound or through which the power of the spring may be exerted to operate any desired device.

Fig. 6 illustrates the preferred method of forming my improved spring, and as shown, there is provided a mandrel 9 having a peripheral configuration conforming to the desired form of spring to be made. A second and similarly shaped mandrel 10 is provided closely adjacent thereto and between these mandrels the wire 1 is drawn over a roller 20 or guide 11 from any suitable source of supply (not shown). The mandrel 9 is mounted upon a shaft 12 which, when rotated, draws the wire 1 from its source of supply and after being formed and shaped between the two 25 mandrels, is wound upon the mandrel 9 until the desired length of spring is wound, whereupon it may be removed and is ready for use.

An adjusting screw 13 is provided whereby the pressure between the two mandrels 9 and 10 may be adjusted, and also for accommodating various sizes of wire.

In Fig. 7, I have shown a modified form of apparatus and method of forming my improved spring comprising a mandrel 14 mounted upon a rotatable shaft 15. This mandrel is provided with the desired peripheral form for the shape of the spring desired, and one end of the spring secured thereto. Upon rotation of the mandrel step by step, or intermittently, the wire 1 is wound upon the mandrel and at each partial turn of the mandrel and between movements thereof, a plunger 16 engages with the wire 1 pressing the same into the indentations 17 formed on the periphery of the mandrel whereby the wire conforms to the shape thereof.

Of course, there are many changes which may be made in details of construction and operation without departing from the spirit and scope of my invention. I do not limit myself, therefore, to the exact forms and method herein shown and described, other than by the appended claim.

55 I claim:—

A spring comprising a plurality of convolutions of spring wire wound side by side, said convolutions being indented at points around and extending inwardly from their peripheries, said indentations being in substantial alignment when said spring is free from tension.

FREEMAN H. OWENS.
